UNITED STATES PATENT OFFICE.

RAYMOND G. BULLOCK, OF JAMESTOWN, NEW YORK, ASSIGNOR TO ART METAL CONSTRUCTION COMPANY, INC., OF JAMESTOWN, NEW YORK, A CORPORATION OF MASSACHUSETTS.

LOCK-ROD FOR FILING-CABINETS.

1,284,581.

Specification of Letters Patent. Patented Nov. 12, 1918.

Application filed November 27, 1917. Serial No. 204,217.

To all whom it may concern:

Be it known that I, RAYMOND G. BULLOCK, a citizen of the United States, residing at Jamestown, county of Chautauqua, and 5 State of New York, have invented new and useful Improvements in Lock-Rods for Filing-Cabinets, of which the following is a specification.

This invention relates to rods for retaining cards and the like in a drawer or other filing receptacle, and the object of the invention is to provide for locking the rod against unauthorized removal, and also to provide for conveniently releasing the rod 15 by the manipulation of a key so as to permit the removal of the rod from a series of cards or the like and thereby permit the addition of new cards or the removal of any of the cards.

With these and other objects in view, the present invention consists in the combination and arrangement of parts, as will be hereinafter more fully described, shown in the drawings and particularly pointed out 25 in the appended claims, it of course being understood that changes in the form, proportion, size and minor details may be made, within the scope of the appended claims, without departing from the spirit or sacrificing any of the features of the invention.

In the accompanying drawings,

Figure 1 is a fragmentary perspective view of a filing drawer equipped with a lock rod of the present invention.

Fig. 2 is an enlarged vertical sectional view taken on the line 2-2 of Fig. 1.

Fig. 3 is a fragmentary sectional view taken through the front end of the rod and the drawer and showing a key in position to 40 release the rod.

Fig. 4 is a detail perspective view of the front end of the rod.

Fig. 5 is a plan section on the line 5-5 of Fig. 2.

Fig. 6 is a fragmentary detail sectional view taken on the line 6-6 of Fig. 5.

Fig. 7 is a detail plan view of the blank which constitutes the support or housing for the locking mechanism.

Fig. 8 is a detail view of the key.

Like characters of reference designate corresponding parts in each of the figures of the drawings.

To illustrate the application of the pres-

ent invention, there has been shown in the 55 accompanying drawings a filing drawer 1 of any preferred or approved form. This drawer may be provided with a suitable track 2 of any preferred form for the slide- able support of a suitable follower, not 60 shown. To accommodate the present invention, the track 2 terminates short of the front of the drawer, as best shown in Fig. 2. The track may be held in place in any suitable manner, say for instance by means 65 of screws, one of which has been shown at 3 in Fig. 2. The card retaining rod 4 is of the usual or preferred form, preferably cy- lindrical in shape, and in accordance with 70 the present invention, is provided at its for- ward end with an enlarged cylindrical head 5. The front end of this head is at right angles to the longitudinal axis of the rod, while the rear or inner end is beveled or 75 tapered rearwardly, as at 6, for a purpose as will hereinafter appear. About midway of the length of the head there is an annular groove 7 which provides front and rear an- nular shoulders 8 and 9. A key slit 10 ex- 80 tends longitudinally of the head and inter- 85sects one longitudinal edge of the head. The front end of this slit intersects the front extremity of the head diametrically thereof, while the inner end of the slit terminates adjacent the tapered end of the head. As clearly shown in Figs. 2 and 3, the slit 10 90 intersects the opposite edge or side of the head through the groove portion thereof and through a portion of the rear or inner part of the head, but does not intersect said 95 side of the head in front of the groove.

The headed end of the rod occupies a cir- 95 cular opening 11 in the front of the drawer, and is normally contained within a bushing 12, the front end of which lies in the open- 100 ing 11 flush with the front face of the front of the drawer. For the support of this bush- 105 ing 12 there is provided a frame or housing consisting of a top plate or member 13 hav- 100 ing a front depending flange 14 lying 105 against the back of the front of the drawer and resting at its lower edge on the bottom of the drawer. The front end of the bush- 110 ing is received within a circular opening 15 in the flange 14, while the rear end of the bushing abuts against a depending leg 16 115 at the back edge of the plate 13. An open- 120 ing 17 is provided in the leg 16 in aline-

ment with the opening 15 but smaller in diameter than the latter, in order to accommodate the rod 4 when the head thereof is lying within the bushing, which latter is 5 of a size to neatly receive the head. The bushing is held in place by means of a suitable fastening 18 piercing the top of the frame or housing and engaging an opening in the bushing. In the top of the bushing 10 there is a transverse notch or opening 19, from which a slit 20 extends forwardly and intersects the front end of the bushing. The top plate 13 is provided with an opening 21 in alinement with the notch 19 in 15 the top of the bushing. A spring arm 22 is disposed upon the top 13 of the frame or housing and has one end secured thereto by suitable fastening means 23. The free end portion of the spring arm is provided 20 with a depending loop or offset 24 which extends downwardly through the opening 21 and into the notch 19 in the bushing 15. When the rod 4 is in place, the part 24 of 25 the locking arm 22 occupies the upper side of the groove 7 in the head 5 and thereby locks the rod against endwise movement, authorized or otherwise. The free extremity 25 of the locking arm constitutes a stop for engagement with the top plate 13.

30 Access to the locking mechanism is prevented by means of a cover plate 25' suitably secured within the drawer. As shown in the drawing, the lower edge of the cover plate rests upon the bottom of the drawer 35 and against the front end of the track 2, while the upper edge of the cover plate is provided with a flange 26 sprung into the beaded upper edge 27 of the front of the drawer. A side flange 28 is provided at 40 each upper edge portion of the cover plate 25' and above the top edge of the adjacent side of the drawer so as to close the space between the cover plate and the flanged up-right side of the front of the drawer.

45 For the purpose of releasing the rod there is provided a key 29 having a straight flat shank provided at one end with a suitable head or handle 30. The other end of the shank is provided with a depending foot 50 portion 31 having a shoulder 32 at its front end. Opposite the foot 31, the other edge of the shank is beveled or inclined downwardly, as at 33.

To release the rod, the key is thrust end- 55 wise into the key slit 10, care being taken to have the foot 31 next to the closed edge of the key slit. As the key is thrust into the slit, the beveled portion 33 of the key engages the under side of the depending portion 24 of the spring locking arm and raises 60 the same out of the groove or seat in the head of the rod, and when the foot 31 of the key clears the bottom of the slit 10, it drops into the open portion of the slit which ex- 65 tends across the groove or seat 7. The size

of the foot 31 is such that it substantially occupies this open side of the slit, and by merely withdrawing the key, the rod may be withdrawn therewith by reason of the shoulder 32 engaging the front shoulder 8 70 on the head of the locking rod. Of course the key is proportioned to hold the spring locking arm 22 out of the seat 7 of the head 5 until the rear portion of the head comes beneath and supports the spring locking 75 arm out of the seat 7. When the rod has thus been withdrawn, cards may be added or removed, as desired. The rod may be replaced by thrusting it endwise through the bushing. In replacing the rod, the 80 beveled or tapered inner end portion 6 of the head forces the spring locking arm 22 upwardly so as to permit the convenient insertion of the rod, after which the locking arm snaps back into the seat or groove 7 85 in the head and locks the rod against unauthorized removal.

The rod is capable of being turned upon its axis within the bearing afforded by the bushing 12, and therefore the rod may be 90 put in place without care to bring the key slit 10 in alinement with the slit 20 in the bushing. By reason of the beveled portion 33 of the key, the extremity of the latter is reduced sufficiently to permit of said extremity being entered into the front end of the slit 10 and thereafter turned so as to turn or rotate the rod and bring the slit 10 in alinement with the slit 20, whereupon the key may be thrust into the head 100 of the rod to release the same from the spring arm or latch.

It is important that the key slot 10 should be as narrow as possible consistent with considerable strength for the key, in 105 order to prevent, as far as possible, the thrusting of a nail or other implement to lift the locking member 22.

Having thus described the invention, what I claim, is:—

110

1. The combination of a card retaining rod having an annular seat and provided with a longitudinal key slot intersecting opposite sides of the seat, said key slot being closed at one side in front of the annular seat, a locking member for engagement with the seat, and a key capable of being thrust into the key slot to force the locking member out of the seat, said key having a projection to engage against the rear side of 115 the shoulder formed by the closed side of the key slot, whereby the key may be employed to pull the rod endwise when the locking member has been displaced from the seat.

125

2. The combination of a card retaining rod having an annular seat and provided with a longitudinal key slot intersecting opposite sides of the seat, said key slot being closed at one side in front of the annular 130

seat, a locking member for engagement with the seat, and a key capable of being thrust into the key slot to force the locking member out of the seat, said key having a beveled portion to bear against and force the locking member out of the seat, and also provided with a lateral projection opposite the beveled portion and adapted to engage the rear side of the closed portion 10 of the key slot, whereby the key may be employed to move the rod endwise when the locking member is displaced from the key.

3. The combination of a card retaining 15 rod having an annular seat and provided with a key slot intersecting opposite sides

of the seat, said key slot being closed at one side in front of the annular seat, a locking member having a part engaging the seat at that side of the rod which is diametrically opposite the closed part of the key slot, and a key capable of being thrust into the key slot and having a beveled edge portion to engage the locking member and force it out of the seat, the key being provided 25 with a lateral projection opposite the beveled portion and of a length substantially equal to the width of the seat and adapted to engage the rear side of the closed portion of the key slot, substantially as and for 30 the purpose described.

RAYMOND G. BULLOCK.
